[57] CLAIM

The ornamental design for a venetian shutter, as shown and described.

DESCRIPTION

FIG. 1 is a front elevation view of a first embodiment of the venetian shutter,

FIG. 2 is a right side view, which is simultaneously a left side view of the first embodiment thereof,

FIG. 3 is a top plan view of the first embodiment thereof,

FIG. 4 is a bottom view of the first embodiment thereof,

FIG. 5 is a rear elevation view of the first embodiment thereof,

FIG. 6 is a cross-sectional view along with the line VI—VI in FIG. 1,

FIG. 7 is a cross-sectional view along with the line VII—VII in FIG. 1,

FIG. 8 is a perspective view on a reduced scale of the first embodiment thereof,

FIG. 9 is an enlarged partial view of the first embodiment thereof,

FIG. 10 is a front elevation view of a second embodiment of the venetian shutter, side, top plan and bottom views of the second embodiment being identical to FIGS. 2, 3 and 4, respectively,

FIG. 11 is a rear elevation view of the second embodiment thereof,

FIG. 12 is a perspective view, on a reduced scale, of the second embodiment thereof, and

FIG. 13 is an enlarged partial view of the second embodiment thereof.
